ATTORNEY

UNITED STATES PATENT OFFICE

GEORGE M. BICKNELL, OF ST. LOUIS, MISSOURI, ASSIGNOR TO CARTER CARBURETOR CORPORATION, OF ST. LOUIS, MISSOURI, A CORPORATION OF DELAWARE

CARBURETOR

Application filed November 16, 1928. Serial No. 319,945.

This invention relates to carburetors and more particularly to a means for controlling the fuel supply to the fuel nozzle.

In the operation of carburetors with the present designs of internal combustion engines, it has been found possible to operate with a lean mixture throughout the throttle valve openings used under ordinary operating conditions; a rich mixture being desirable only during the starting and when the throttle is open fully or nearly so. In carburetors provided with a starting nozzle or jet it is therefore desirable to adjust the carburetor to provide a lean mixture during the usual openings of the carburetor throttle valve and to provide a means for changing the lean mixture to a rich mixture when the throttle valve is fully open or nearly so. It is therefore an object of this invention to provide means for increasing the richness of the mixture supplied by the carburetor when the throttle valve of the carburetor is opened a predetermined amount and for providing a lean mixture when the throttle valve is closed to less than the predetermined opening. It is also an object of this invention to provide a control for the calibrated orifice of the fuel nozzle which gives an effective opening of one size throughout a predetermined range of the throttle valve opening and gives an opening of another size throughout another range of the throttle valve opening.

With these and other objects in view, as will appear more fully hereinafter, the invention consists substantially in the construction, combination, location and relative arrangement of the parts, all as will be more fully herein set forth, as shown in the accompanying drawings and finally pointed out in the appended claims.

In the drawings:

Figure 1 is a central vertical section of a carburetor provided with means for controlling the metering orifice of the fuel nozzle in accordance with this invention; and

Fig. 2 is a vertical section drawn to a larger scale of the fuel nozzle, bowl plug and metering pin shown in Fig. 1.

In the drawings the invention is shown in connection with a carburetor comprising a

body or casing 1 having an air inlet 2 and a mixture outlet 4. The mixture outlet is provided with a venturi 6 and a throttle valve 8; the throttle valve 8 being mounted on a shaft 10 journaled in the walls of the casing 1. The casing 1 is formed with an extension 12 directed oppositely to the mixture outlet 4 and provided with an irregularly shaped opening 14 therethrough; the enlarged outer end of the opening being closed by a plug 16 threaded in the opening 14 and securing the bowl 18 to the casing 1. The bowl 18 forms the float chamber 20 in which is mounted the float 22 controlling the supply of fuel to the chamber 20 by means of a valve (not shown). In the enlarged outer end of the opening 14 above the plug 16 there is mounted a fuel nozzle 24 which projects beyond the inner or upper end of the opening 14. In the enlarged upper end of the opening 14 is mounted a standpipe 26 which surrounds the upper end of the nozzle 24 and extends into the lower end of the venturi 6. Surrounding the standpipe 26 is a choke valve 28 operated by an arm 30 on a shaft 32 and controlling not only the admission of air to the venturi 6 but the admission of air through the ports 34 to the standpipe 26. The chamber formed by the opening 14 is connected with the float chamber 20 by means of a passage 36 and by means of a passage 38 with an idling tube or jet 40 which communicates through a port 42 with the mixture outlet 4 in the region of the throttle valve 8. The base of the standpipe 26 is provided with an opening 46 through which communication is established between the air inlet 2 and the chamber formed by the opening 14, and the standpipe 26 is provided with an opening 48 establishing communication between the air inlet 2 and the interior of the standpipe 26.

The passage 49 through the fuel nozzle 24 is constricted as at 50, and mounted for reciprocation in the passage 49 is a metering pin 52 connected by a link 54 to an arm 56 rigidly attached to the throttle valve 8. The metering pin 52 is of substantially uniform diameter from its point of connection with the link 54 to within a short distance from its other end where its diameter is reduced as

at 58; the length of the portion 60 of greater diameter being such that in the usual operation positions of the throttle valve 8 the portion 60 enters the constricted opening 50 in the fuel passage 49 of the nozzle 24 and determines the effective opening of the nozzle 24. When the valve 8 is approximately seven-eighths open, the portion 60 leaves the constricted opening 50, after which the portion 58 of less diameter determines the effective opening in the constricted portion 50 and gives a larger effective opening in the constricted portion of the fuel nozzle. It will be noted that the plug 16 is provided with a recess 62 in which the reduced portion 58 of the metering pin fits; the plug 16 engaging the reduced portion 58 of the metering pin and serving to guide the metering pin and prevent wear of the fuel nozzle at the constricted portion 50 and change in the calibration of the opening.

From the above it is seen that during the usual opening of the throttle valve 8 a fuel opening of one size is provided, and that as soon as the opening of the throttle valve 8 exceeds a predetermined amount the portion 58 of the metering pin is brought to the constricted portion 50 and a fuel opening of greater area provided permitting of increased flow of fuel to the nozzle and providing a richer mixture. It will of course be understood that the point at which the greater effective area of the nozzle 24 becomes operative may be varied by changing the relative proportions of the portions 58 and 60 of the metering pin 52.

The drawings herein disclose the preferred embodiment of the invention, but it is to be understood that they are merely by way of example and that various changes in form and proportions of the device may be made within the scope of the appended claims without departing from the spirit of the invention.

45. What is claimed is:

1. In a carburetor, a body member having a bore, a fuel nozzle threaded into said bore having a fuel passage formed with a constricted portion therein, a metering pin mounted in said nozzle and determining the effective opening of the constricted portion of said nozzle, and a guide member for said metering pin also threaded into said bore.

2. As an article of manufacture, a combined bowl retaining nut and metering rod protector for carburetors comprising a body member having a screw threaded portion adapted to be threaded into a corresponding screw threaded bore in the body of a carburetor, said body member having a flange at the inner end of said thread, said flange being adapted to engage the bowl of the carburetor and to hold it tightly against the end of the body member, and a longitudinal bore in said body member, said bore being

open at the inner end to receive and protect the metering rod of the carburetor, said bore being closed at its outer end to prevent the escape of fuel from the carburetor.

3. In a carburetor, a main body member having a downwardly extending portion, an annular seat surrounding said downwardly extending portion, a cup-shaped bowl having an upper rim adapted to engage said seat, the bottom of said bowl having a concentric perforation therein and being adapted to be held against the end of said downward extension, a vertically extending opening in said main body member, a rod extending through said opening and downwardly through the perforation in the bowl, and a single means forming a housing for the extension of said rod and retaining said bowl in position.

4. In a device of the class described having a main body member, an annular seat on said body member, a cup shaped bowl having its rim engaging said seat, an extension of said body member substantially co-axial with said seat and extending into said bowl; a longitudinal passageway in said extension, a transverse passageway providing communication between said bowl and said longitudinal passageway, means forming a restricted portion in said longitudinal passageway, a longitudinal moveable control rod extending through the passageway to control the effective area of the restricted portion and protruding beyond the end of said extension, screw threads in the end of said extension, and a perforation in the end of said bowl registering with said thread; the improvement comprising a screw threaded nut having a flange adapted to engage the end of said bowl and hold the same firmly in place when the nut is screwed into the said extension, said nut having an axial bore open only at its inner end for housing and protecting the protruding end of said control rod.

5. In a carburetor of the type having a main body member having a passageway therethru, a screw threaded enlarged portion at one end of said passageway, a nozzle threaded into said enlarged portion, a metering orifice in said nozzle, a cup shaped bowl having an opening in its bottom, said bowl being mounted in surrounding relation to the end of the body member and with the opening in registration with the end of the enlarged passageway, a bore in the body member connecting the enlarged portion of the passageway with the interior of the bowl, and a longitudinally movable control rod extending thru the passageway and the metering orifice to control the same, the improvement comprising a member passing thru the perforation in the bowl and screw threaded into the enlarged portion of said

passageway to close the same, said last named member having a flange for holding the bowl firmly against the end of the body member, and having a concentric bore to receive the end of the rod.

5 In witness whereof I have hereunto set my hand.

GEORGE M. BICKNELL.
